UNITED STATES PATENT OFFICE.

CHARLES R. BIRDSEY, OF HINSDALE, ILLINOIS, ASSIGNOR, BY MESNE ASSIGNMENTS, TO UNITED STATES GYPSUM COMPANY, OF CHICAGO, ILLINOIS, A CORPORATION OF ILLINOIS.

PLASTER-BOARD.

1,395,031.

Specification of Letters Patent. Patented Oct. 25, 1921.

Application filed January 2, 1920. Serial No. 348,940.

To all whom it may concern:

Be it known that I, CHARLES R. BIRDSEY, a citizen of the United States, residing at Hinsdale, in the county of Du' Page and 5 State of Illinois, have invented certain new and useful Improvements in Plaster-Board, (Case B,) of which the following is a description.

My invention belongs to that general class 10 of devices known as plaster board or the like, and relates particularly to an improved board which will be simple, convenient, substantial, durable, satisfactory and efficient, and which may be economically and accurately manufactured. The invention relates 15 particularly to a type of board in which the plaster, plaster Paris or plastic material body is substantially inclosed on one or both opposite edges, as well as on the 20 face sides, and in which the edges may be perfectly formed to conform to a definite specification as to size or angle. Many other objects and advantages of the construction herein shown and described will be obvious 25 to those skilled in the art from the disclosures herein given.

To this end my invention consists in the novel construction, arrangement and combination of parts herein shown and described, and more particularly pointed out 30 in the claims.

In the drawings, wherein like reference characters indicate like or corresponding parts,

35 Figure 1 is a sectional view through a portion of a plaster board embodying the invention;

Fig. 2 is a perspective view of a portion of the board;

40 Fig. 3 is a similar view of a slightly modified construction; and

Fig. 4 is a similar view of another slightly modified construction.

Referring to the drawings, particularly 45 Figs. 1 and 2, 1 represents a body of suitable material, as for example plaster, plaster Paris, or any equivalent suitable for the purpose, which may be handled in a plastic state and thereafter allowed to set or harden. 50 The body is inclosed between the covering sheets 2 and 3 of suitable covering material, and in this connection it may be mentioned that I have found that paper of the desired weight or thickness very satisfactory 55 for the purpose.

In the type illustrated in Fig. 1, one or both edges 4 of one of the covering sheets, as shown sheet 2, are folded toward the covering sheet 3 so as to inclose the plastic material at the edges of the board. Ordinarily I prefer to score the sheet 2, as indicated at 7, so that a perfect corner 5 may be formed, the particular contour of the edge 4, however, being as desired. In this type the upturned edge 4 is brought to meet 65 with the end 6 of the covering sheet 3, the same being of a width so that the free edge 8 is substantially flush with the top face of the board. Generally the edges 4, which may be turned up as mentioned on one or 70 both sides, will adhere to the plastic body, so that it is unnecessary to use additional ingredients or material to secure the same in place. A portion of the material will leak between the edge 6 of the top sheet 75 and the side 4, securely sealing and securing the two together.

In the construction shown in Fig. 3, 11 represents a plastic body and 12 and 13 the covering sheets, one of which may be scored 80 as at 17 and bent or folded over as at 15 so as to provide the edge covering 14 at one or both sides. In this case the top covering sheet is of sufficient width so that its under face at 16 overlies the free edge 18 under 85 the side 14.

In the construction shown in Fig. 4, 21 represents the plastic body and 22 and 23 the covering sheets. In this case, one sheet is bent or folded to form an edge 24 at one 90 or both sides, the same being preferably scored as at 27 so as to form a sharp corner at 25. The cover sheet 23 is preferably of a width to form an overlapping end portion 26, the same being scored as at 27 so as to 95 provide a sharp corner if desired. In this case the edge 26 is of a length to engage with its edge 28 overlying the edge of the body, and if desired, extending to the cover sheet 22. The extreme edge 29 of the overlying portion 24 may extend to flush with the extreme face of the cover sheet 23 if so desired. In constructing this type, while the overlying or overlapping edges 26 and 24 may be secured together in any suitable 100 manner, ordinarily enough plaster or plaster Paris, if the body is constructed of this or its equivalent, may flow up between the two upturned edges 24 and 26, securely sealing the same and maintaining the parts together. 105 110

It will be noted that with all of these constructions, the edge is substantially completely inclosed, and as before mentioned, this may be at one or both sides. If the two sheets are integral and wrapped or folded over one edge, or it is desired to only inclose one edge, then this construction might only be employed at one edge, the opposite edge being different. The resulting product 10 is produced with a straight, smooth edge and at a perfect angle, the board being uniform in width throughout its length. The completed product has many advantages, and it has increased strength and durability, 15 and an improved appearance. In case of handling, the edges are protected and there is no breaking away nor sifting out or powdering of the body at the edge.

Having thus described my invention, it is 20 obvious that various immaterial modifications may be made in the same without departing from the spirit of my invention; hence I do not wish to be understood as limiting myself to the exact form, construction, arrangement and combination of 25 parts herein shown and described, or uses mentioned.

What I claim as new and desire to secure by Letters Patent is:

- 30 1. A plaster board of the kind described comprising a body and a covering sheet arranged at each face side thereof, one of said sheets folded over the edge and extending substantially to and terminating at the opposite face and inclosing the edge.
- 35 2. A plaster board of the kind described

comprising a body, and a covering sheet arranged at each face side thereof, one of said sheets being folded over one edge of the body and extending substantially to the opposite face side with its edge lying substantially flush with the outer face of the covering sheet at said face side. 40

3. A plaster board comprising a body, and covering sheet portions on two adjoining 45 angularly related faces of the body, one of the covering sheet portions terminating substantially at the meeting edge of said faces, and the other sheet portion extending beyond said meeting edge substantially flush 50 with the outer face of the other covering sheet portion and overlying the adjoining edge thereof.

4. A plaster board comprising a body, and covering sheet portions on two adjoining 55 angularly related faces of the body, the covering sheet portion on one of said faces having an end portion extending flush with the other of said faces, and the other covering sheet portion extending beyond the 60 meeting edge of said faces substantially flush with the outer face of the other covering sheet portion and overlying the adjoining end part thereof.

In testimony whereof, I have hereunto 65 signed my name in the presence of two subscribing witnesses.

CHARLES R. BIRDSEY.
